MULTIPLE POSITION RECLINING CHAIR

Fridtjof F. Schliephacke, Berlin-Schmargendorf, Germany, assignor to Anton Lorenz, Boynton Beach, Fla.

Filed Oct. 28, 1958, Ser. No. 770,079

10 Claims. (Cl. 155—106)

The present invention relates to improvements in reclining chairs of the type which includes a movable body-supporting unit comprising a seat and back-rest and a movable leg-rest mounted at the forward end of the chair for coordinated movement with the body-supporting unit. In particular, this invention relates to a reclining chair in which the seat and back-rest are formed as a rigid unit which is mounted on a support frame for movement between a normal sitting position, an intermediate partially-tilted position, and a fully-tilted position.

The well-known reclining chair presently on the market comprises generally a seat and back-rest structure in which the seat and back-rest may be rigid with each other and pivoted as a unit on the support frame, or in which the seat and back-rest may be independently pivoted on the support frame for movement relative to each other. A leg-rest is normally connected through a linkage to the seat and back-rest structure and/or to the support frame in such a manner as to be provided with coordinated movement in response to movement of the seat and back-rest structure. The usual reclining chair has been designed to permit the body-supporting unit to move from a normal upright sitting position in which the leg-rest is in a retracted position beneath the seat, to a reclined position in which both seat and back-rest are rearwardly tilted and the leg-rest is in an extended position.

A recent development in reclining chairs has been the "two-position" chair in which a body-supporting unit comprising a rigid seat and back-rest is mounted on the support for movement through a first motion phase from the sitting position to intermediate, partially-tilted position and then through a second motion phase to a fully-tilted position in which the body-supporting unit is inclined at a maximum angle relative to the support frame. The chair is generally provided with a leg-rest and a control mechanism for the leg-rest, the control mechanism being adapted to bring the leg-rest from a retracted position to an extended position during the first motion phase and to maintain it in the extended position during the second motion phase.

It is an object of the present invention to provide a "two position" reclining chair having an improved guiding means for bringing the body-supporting unit to its intermediate and fully-tilted positions.

Another object of the invention is to provide a reclining chair of the type described in which the guiding means is adapted to move the body-supporting unit in a substantially horizontal rearward direction during the first motion phase, and then in a simple pivoting rearward motion during the second motion phase.

Still another object of the invention is the provision of a reclining chair of the character described having an improved leg-rest control structure which is coordinated in movement with the body-supporting unit for bringing the leg-rest to its extended position during the first motion phase and retaining it in an extended position during the second motion phase.

In accordance with the invention, there is provided a reclining chair having a rigid body-supporting unit, with a pair of guide links mounting the same on the support frame. The rear guide link is mounted by a fixed pivot on the support frame. The front guide link is mounted on the support frame by a movable pivot in the nature of a pin and slot connection. During the first motion phase, the body-supporting unit is moved rearwardly by the rearward pivoting of both guide links. At the intermediate tilted position, the rear guide link engages a stop member so that it cannot pivot further rearwardly, and the body-supporting unit pivots further rearwardly in the second motion phase about its pivotal connection on the rear guide link. During this second motion phase, the pin and slot connection of the front guide link with the support permits the front guide link to rise with the forward end of the seat.

The leg-rest is mounted on the front of the seat and is connected by a single control link to the support in such a manner that when the unit is brought to its intermediate tilted position and the front end of the seat is raised, the control link pivots upwardly to raise the leg-rest from a retracted position to an extended position, and, by suitable location of the various pivot points, is prevented from pivoting downwardly, thereby maintaining the leg-rest in said extended position. When the unit is brought to its fully-reclined position, the control link pivots upwardly to maintain the leg-rest in its extended position.

Additional objects and advantages of the invention will be apparent during the course of the following specification when taken in connection with the accompanying drawings, in which:

Fig. 1 is a side elevational view of a reclining chair made in accordance with the present invention and shown in its upright sitting position, with parts broken away and shown in section to reveal inner constructional detail;

Fig. 2 is a similar side elevational view of the chair illustrated in Fig. 1, but showing the body-supporting unit in an intermediate tilted position and the leg-rest in extended position; and

Fig. 3 is a similar side elevational view of the chair illustrated in Figs. 1 and 2, but showing the body-supporting unit in a fully-tilted position and the leg-rest in a corresponding extended position.

Referring in detail to the drawings, there is shown a reclining chair which includes a support frame or base structure 10 having depending legs 12 for maintaining it above the floor level. A body-supporting unit, designated generally by the reference numeral 14, is movably mounted on the support frame 10. The body-supporting unit 14 comprises a seat 16 and a back-rest 18 which are formed integrally with each other to provide a rigid unit.

The body-supporting unit 14 is mounted on the support 10 for rearward movement by a pair of guide links 20 and 22 which are connected at their upper ends to spaced points on the lower portion of the seat 16 by respective pivots 24 and 26. The pivots 24 and 26 may be connected directly to the seat 16, but are preferably connected to depending lugs 28 and 30 which form a rigid portion of the seat 16.

At its bottom end the rear guide link 22 is pivotally mounted on the support frame 10 by a pivot 32. At its lower end, the front guide link 20 is pivotally connected to the support frame 10 by a pivot pin 34. The mounting of the front guide link 20 on the support frame 10 is, however, a slide connection provided by an elongated slot 36 at the lower end of the front guide link 20, the slot 36 receiving the pivot pin 34. The pin and slot connection 34, 36 provides a means whereby the front guide link 20 is normally pivotable on the support frame 10,

but during a portion of its movement may be raised relative to the support frame, in a manner which will be presently explained.

A stop member 38 is formed rigidly with the support frame 10 and may constitute a cross brace thereof. This stop member 38 is positioned to be engaged by the rear guide link 22 in the upright sitting position of the chair shown in Fig. 1, whereby the stop member 38 prevents forward pivoting movement of the rear guide link 22 about its pivotal mount 32, and therefore supports the body-supporting unit 14 in the upright sitting position. A second stop member 40, which is also rigid with the support frame 10, is located to the rear of the rear guide link 22 in a position to engage the rear guide link 22 and stop the rearward pivoting thereof in the intermediate tilted position shown in Fig. 2. A third stop member 42, also rigid with the support frame 10, is located at the rear of the chair and in a position to engage the lower portion of the body-supporting unit 14 in the fully tilted position of Fig. 3, in a manner which will be presently described.

The position of the chair shown in Fig. 1 represents the upright sitting position thereof in which the occupant is disposed in a normal sitting position as in conventional chairs. In this upright position, the guide links 20 and 22 are inclined forwardly and upwardly, the rear guide link 22 resting upon the first stop member 38 and being restrained thereby from forward pivoting movement, whereby the body-supporting unit 14 is supported in its upright position. The pivot pin 34 is located at the top end of the slot 36, and the portion of the front guide link 20 bordering the top of slot 36 rests upon said pivot pin 34, the latter supporting the weight of the front end of the seat 16.

When the occupant of the chair in the upright sitting position wishes to move to the intermediate tilted position, he shifts his weight rearwardly and applies rearward pressure to the back-rest 18, causing the guide links 20 and 22 to pivot rearwardly about their respective pivotal mounts 34 and 32. This rearward pivoting movement of the guide links 20 and 22 carries the body-supporting unit 14 in a rearward and substantially horizontal direction to the intermediate tilted position of Fig. 2, which position is defined by the engagement of the rear guide link 22 with the second stop member 40. Since the rear guide link 22 can no longer pivot rearwardly about its pivotal mount 32, the body-supporting unit 14 can no longer move in the first motion phase as directed by the two guide links 20 and 22.

It will be noted in Fig. 1 that the front guide link 20 is inclined forwardly to a greater degree than the rear guide link 22. Consequently, as the body-supporting unit 14 approaches the intermediate tilted position, the upper end of the rear guide link 22 has moved downwardly to a greater extent than the upper end of the front guide link 20 and the rear portion of the seat is lowered slightly relative to the front portion thereof, so that the seat is slightly tilted rearwardly in the intermediate tilted position. As will be presently explained, the leg-rest is moved to its extended position during the first motion phase, so that in the intermediate tilted position the occupant's legs are supported by the leg-rest and his body is still in a substantially upright position which is suitable for reading, viewing television or the like.

The intermediate tilted position of Fig. 2 is determined by engagement of the stop member 40 with the rear guide link 22, thereby preventing further rearward pivoting movement of said rear guide link about its pivot 32. In this limit position, the pivot pin 34 is still located at the top of the slot 36 and the front guide link 20 is still resting upon said pivot pin 34.

Since further rearward movement in a substantially horizontal direction is prevented by engagement of the stop member 40 with the rear guide link 22, a different path of movement must be provided to enable the body-supporting unit 14 to be moved from the intermediate

tilted position to a fully-tilted position. This is accomplished by the pivot 26 connecting the rear guide link 22 to the body-supporting unit 14, and also by the pin and slot connection 34 and 36 between the front guide link 20 and the support frame 10. Thus, when the occupant of the seat wishes to move from the intermediate tilted position to a fully-tilted position, he may shift his weight further rearwardly and apply further pressure against the back-rest 18, thereby causing the body-supporting unit to pivot about its pivotal connection 26 with the rear guide link 22 in the manner shown in Fig. 3. It will therefore be appreciated that the movement of the body-supporting unit 14 through the second motion phase is a simple pivoting movement of its center portion about the pivot 26 which is now fixed relative to the support frame, so that the rear portion of the body-supporting unit 14 is lowered and the front portion is raised. This pivoting movement is permitted by the pin and slot connection 34, 36 of the front guide link 20, the slot 36 enabling the front guide link 20 to rise relative to the support 10 so that in the fully-tilted position of Fig. 3 the pin 34 is located at the bottom of the slot 36. The limit of movement of the body-supporting unit 14 during the second motion phase is determined by engagement of the pin 34 with the bottom end of the slot 36, and also by engagement of the lower surface of the seat 16 with the third stop member 42.

The chair structure also includes a leg-rest 50 mounted on the seat 16 for movement between a retracted position shown in Fig. 1 to the extended positions shown in Figs. 2 and 3. The leg-rest 50 is carried by an angular mounting arm 52, the free end of which is pivotally mounted on the front end of the seat 16 by a pivot 54. The movement of the leg-rest 50 is effected by a control link 56, one end of which is pivotally mounted on the support frame 10 by pivot 58, and the other end of which is pivotally connected to the leg-rest 50 and/or the mounting arm 52 by a pivot 60.

In the upright sitting position of the chair shown in Fig. 1, the control link 56 maintains the leg-rest 50 in its retracted position in which it is inclined rearwardly below the front end of the seat 16. The leg-rest is held from downward pivoting movement by the control link 56, since the leg-rest must pivot downwardly and forwardly in a counterclockwise path about its seat pivot 54, while the control link 56 must pivot downwardly and rearwardly in a clockwise direction about its pivotal mount 58.

When the body-supporting unit 14 is moved rearwardly to its intermediate tilted position of Fig. 2, the leg-rest pivot 54 is moved rearwardly toward the fixed pivot 58 of the control link 56. The control link 56 thus pushes forwardly on the leg-rest 50 at the pivot point 60, causing the leg-rest to pivot upwardly about its pivot 54. When the body-supporting unit reaches its intermediate tilted position, the leg-rest 50 has pivoted to an extended position forwardly of and substantially at the level of the front end of the seat 16 and is held in this position by the control link 56. This holding function of the control link 56 is determined by the difference in the two arcs of travel which the control link and the leg-rest would have to travel at the point 60, in order to pivot downwardly from the extended position of Fig. 2. It will be appreciated that in order for the control link 56 to pivot downwardly, the end of the control link at point 60 must travel through an arc whose radius is the distance between pivot 58 and pivot 60. In order for the leg-rest 50 to pivot downwardly, the portion of the leg-rest at pivot 60 must travel through an arc of smaller radius in a different path, this radius being the distance between the pivot 54 and the pivot 60. Consequently, the leg-rest cannot be lowered from its extended position of Fig. 2 unless the body-supporting unit 14 is moved forwardly, changing the location of pivot 54 relative to the fixed pivot 58.

Should the occupant of the chair wish to return from the intermediate tilted position of Fig. 2 to the upright

sitting position of Fig. 1, a forward shift of the occupant's weight together with pressure of the occupant's legs upon the leg-rest 50 will urge the body-supporting unit 14 forwardly upon the front and rear control links 20 and 22. At the same time, this forward movement of the seat 16 to its retracted position.

If, however, the person sitting in the intermediate tilted position of Fig. 2 wishes to move to the fully-tilted position of Fig. 3, a slight additional rearward pressure against the back-rest 14 will initiate the second motion phase. The body-supporting unit now tilts rearwardly in a simple pivoting movement about the immovable pivot 26 of the rear guide link 22. This movement continues until the rear end of the unit engages the stop member 42 so that the unit is now in the fully-tilted position of Fig. 3 in which the user's body is disposed in an inclined position for a greater relaxation.

As the body-supporting unit moves to the fully-tilted position, the front of the seat 16 is raised and the location of the pivot 54 is changed relative to the fixed pivot 58. The control link 56 therefore pivots further upwardly, in a counterclockwise direction as seen in Figs. 2 and 3, raising the leg-rest 50 relative to the support 10 and maintaining the leg-rest in its extended position at the level of the front of the seat 16, as shown in Fig. 3.

Again, the difference in the pivotal path of the control link 56 and the leg-rest 50 at point 60 maintains the leg-rest in the extended position of Fig. 3, while the body-supporting unit remains in the fully-tilted position. When the person sitting in the fully-tilted position wishes to return to the intermediate tilted position, a forward shift of body weight will cause the unit to pivot forwardly about the rear guide link pivot 26, and the front portion of the seat 16 will be lowered, thereby lowering the front guide link 20 until the pivot pin 34 is again located at the top of the slot 36.

While a preferred embodiment of the invention has been shown and described herein, it is obvious that numerous omission, changes and additions may be made without departing from the spirit and scope of the invention.

I claim:

1. In a reclining chair having a support frame and a body-supporting unit including a seat and a back-rest rigid with each other, a pair of guide links having respective pivotal connections to the front and rear portions of the seat and each pivotally mounted on the support frame for supporting the unit, the front and rear guide links being turnable about their pivotal mounts on the support frame for guiding the body-supporting unit rearwardly from an upright sitting position to an intermediate tilted position in response to rearward pressure against the movable body-supporting unit exerted by an occupant seated in the chair, stop means on the support frame positioned to engage the rear guide link when the unit has reached its intermediate tilted position to block further rearward movement of said unit along both guide links, said stop means immovably holding the rear guide link relative to the support frame whereby further movement of the seat is a pivotal movement about said immovable rear guide link in which the front portion of the unit is raised and the rear portion is lowered, and slide means on the front guide link providing a lost motion upward movement of the front portion of the seat relative to the support frame during said further pivotal movement, of the seat about the rear guide link.

2. In a reclining chair having a support frame and a body-supporting unit including a seat and a back-rest rigid with each other, a pair of guide links pivotally connected to respective front and rear portions of the seat and each pivotally mounted at spaced points on the support frame for supporting the unit, the front and rear guide links being turnable about their pivotal mounts on the support frame for guiding the body-supporting unit

- rearwardly from an upright sitting position to an intermediate tilted position in response to rearward pressure against the body-supporting unit exerted by an occupant seated in the chair, said guide links being forwardly inclined in said upright sitting position and pivoting to a rearwardly inclined position in said intermediate tilted position of the unit, stop means on the support frame positioned to engage the rear guide link when the unit has reached its intermediate tilted position to block further rearward movement of said unit along both guide links, said stop member immovably holding the rear guide link relative to the support frame whereby further movement of the seat is a pivotal movement about the pivotal connection of said immovable rear guide link with the seat to a fully-tilted position in which the front portion of the unit is raised and the rear portion is lowered, the pivotal mount of the front guide link on the support frame comprising a pin and slot connection between the front guide link and the support frame providing a lost motion movement of the front guide link relative to the support frame as the front guide link is lifted with the forward portion of the seat when the seat is turned about its pivotal connection with the immovable rear guide link.
3. In a reclining chair having a support frame and a body-supporting unit including a seat and a back-rest rigid with each other, a pair of guide links having respective pivotal connections to the front and rear portions of the seat and each pivotally mounted on the support frame for supporting the unit, the front and rear guide links being turnable about their pivotal mounts on the support frame for guiding the body-supporting unit rearwardly from an upright sitting position to an intermediate tilted position in response to rearward pressure against the body-supporting unit exerted by an occupant seated in the chair, stop means on the support frame positioned to engage the rear guide link when the unit has reached its intermediate tilted position to block further rearward movement of said unit along both guide links, said stop member immovably holding the rear guide link relative to the support frame whereby further movement of the seat is a pivotal movement about said immovable rear guide link in which the front portion of the unit is raised and the rear portion is lowered, and slide means on the front guide link for permitting the front portion of the seat to be raised relative to the support frame during said further movement, a leg-rest, and leg-rest control means for moving said leg-rest from a retracted position beneath the seat to an extended, leg-supporting position forwardly of the seat during the first motion phase, and maintaining the leg-rest in an extended leg-supporting position during the second motion phase, said leg-rest control means comprising pivot means mounting the leg-rest on the forward end of the seat and a control link pivotally mounted on the support and pivotally connected to the leg-rest at a point spaced from the pivotal mount of the leg-rest on the seat.
4. In a reclining chair having a support frame and a body-supporting unit including a seat and a back-rest rigid with each other, a pair of guide links pivotally connected to respective front and rear portions of the seat and each pivotally mounted at spaced points on the support frame for supporting the unit, the front and rear guide links being turnable about their pivotal mounts on the support frame for guiding the body-supporting unit rearwardly from an upright sitting position to an intermediate tilted position in response to rearward pressure against the body-supporting unit exerted by an occupant seated in the chair, said guide links being forwardly inclined in said upright sitting position and pivoting to a rearwardly inclined position in said intermediate tilted position of the unit, stop means on the support frame positioned to engage the rear guide link when the unit has reached its intermediate tilted position to block further rearward movement of said unit along both guide

links, said stop member immovably holding the rear guide link relative to the support frame whereby further movement of the seat is a pivotal movement about the pivotal connection of said immovable rear guide link with the seat to a fully-tilted position in which the front portion of the unit is raised and the rear portion is lowered, the pivotal mount of the front guide link on the support frame comprising a pin and slot connection mounting the front guide link on the support frame for upward sliding movement, whereby the front portion of the seat is raised relative to the support frame during said pivotal movement of the seat, a leg-rest, and leg-rest control means for moving said leg-rest from a refracted position beneath the seat to an extended, leg-supporting position forwardly of the seat during the first motion phase and for maintaining the leg-rest in an extended leg-supporting position during the second motion phase, said leg-rest control means comprising pivot means mounting the leg-rest on the forward end of the seat and a control link pivotally mounted on the support and pivotally connected to the leg-rest at a point spaced from the pivotal mount of the leg-rest on the seat.

5. A reclining chair according to claim 4 in which the distance between the pivotal mount of the control link on the support and the pivotal connection of the control link to the leg-rest is longer than the distance between the pivotal mount of the leg-rest on the seat and the connection of the control link to the leg-rest, whereby the leg-rest is retained in an extended leg-supporting position during both the intermediate tilted and fully-tilted positions of the unit.

6. A reclining chair comprising a support frame, a rigid seat and back-rest unit, and means movably mounting said unit on said support frame, said mounting means including front and rear guide links pivotally connected to spaced points on the seat, a fixed pivot mounting the rear guide link on the support frame, a pin and slot connection pivotally mounting the front guide link on the support frame, the body-supporting unit being movable in a first motion phase in which it is guided rearwardly relative to the support frame by both front and rear guide links in response to rearward pressure against the body-supporting unit exerted by an occupant seated in the chair, to an intermediate tilted position, stop means on the support frame engageable with the rear guide link at the end of said first motion phase to retard further rearward movement of the body-supporting unit relative to the fixed pivot of the rear guide link, the body-supporting unit being then movable in a second motion phase constituting a pivotal movement of said seat about the pivotal connection between the seat and said rear guide link, the pin and slot connection providing a lost motion movement during the second motion phase for permitting the front guide link to be raised relative to the support frame, whereby said front guide link is lifted with the forward portion of the seat during said second motion phase.

7. In a reclining chair having a support frame and a body-supporting unit including a seat and a back-rest rigid with each other, front and rear guide means mounting said body-supporting unit on said support frame and movable in a first motion phase in response to rearward pressure against the body-supporting unit exerted by an occupant seated in the chair to carry said body-supporting unit in a compound movement from an upright sitting position to a rearwardly-tilted position, a pivotal connection between said body-supporting unit and the rear guide means, said pivotal connection moving rearwardly during said first motion phase, the front guide means comprising a link pivotally connected to the forward portion of the seat and to the support frame, stop means positioned to engage at least one of said front and rear guide means at said intermediate tilted position to halt further movement of both said front and rear guide means, and slide means on said link extensible to permit upward movement of the forward end of the seat away

from the pivotal connection of the front guide link with the support frame during a second motion phase of the body-supporting unit from said intermediate tilted position to a fully-tilted position, the body-supporting unit turning about the pivotal connection between the body-supporting unit and the rear guide means during said second motion phase.

8. In a reclining chair having a support frame and a body-supporting unit including a seat and a back-rest rigid with each other, front and rear guide means mounting said body-supporting unit on said support frame and movable in a first motion phase from an upright sitting position to a rearwardly-tilted position in response to rearward pressure against the body-supporting unit exerted by an occupant seated in the chair, said rear guide means comprising a link pivotably mounted on the support frame and a pivotal connection between said body-supporting unit and said link, said pivotal connection moving rearwardly with said link during said first motion phase, stop means positioned to engage at least one of said front and rear guide means at said intermediate tilted position to halt further movement of both said front and rear guide means, said front guide means including slide means extensible to permit upward movement of the forward end of the seat relative to the support frame during a second motion phase of the body-supporting unit from said intermediate tilted position to a fully-tilted position, the body-supporting unit turning about the pivotal connection between the body-supporting unit and said link during said second motion phase.

9. In a reclining chair having a support frame and a body-supporting unit including a seat and a back-rest rigid with each other, front and rear guide links, a first pair of pivots respectively connecting the front and rear guide links to the front and rear portions of the seat, a second pair of pivots respectively mounting the front and rear guide links on the support for supporting the body-supporting unit and providing two centers of rotation on the support for rearward movement of the body-supporting unit about both centers of rotation through a first motion phase to an intermediate tilted position in response to rearward pressure exerted by the occupant seated in the chair against the body-supporting unit, stop means on the support frame engageable with at least one of said guide links for blocking further rearward movement of said unit about said two centers of rotation at the intermediate tilted position, and slide means between the front guide link and the support frame at the pivotal mount of said front guide link, said slide means providing a lost motion movement of the front guide link relative to the support at the end of the first motion phase to permit the body-supporting unit to turn about the pivotal connection of the blocked rear guide link with the body-supporting unit during a second motion phase in which the unit moves rearwardly from the intermediate tilted position to a fully-tilted position.

10. In a reclining chair having a support frame and a body-supporting unit including a seat and a back-rest rigid with each other, front and rear guide links, a first pair of pivots respectively connecting the front and rear guide links to the front and rear portions of the seat, a second pair of pivots respectively mounting the front and rear guide links on the support for supporting the body-supporting unit and providing two centers of rotation on the support for rearward movement of the body-supporting unit about both centers of rotation through a first motion phase to an intermediate tilted position in response to rearward pressure exerted by the occupant seated in the chair against the body-supporting unit, stop means on the support frame engageable with at least one of said guide links for blocking further rearward movement of said unit about said two centers of rotation at the intermediate tilted position, and slide means between the front guide link and the support frame at the pivotal mount of said front guide link, said slide

means providing a lost motion movement of the front guide link relative to the support at the end of the first motion phase to permit the body-supporting unit to turn about the pivotal connection of the blocked rear guide link with the body-supporting unit during a second motion phase in which the unit moves rearwardly from the intermediate tilted position to a fully-tilted position, a leg-rest, and control means mounting the leg-rest on the chair for movement from a retracted position beneath the seat to an extended leg-supporting position in response to movement of the body-supporting unit during the first motion phase to the intermediate tilted position, and

5

for further movement to a further extended leg-supporting position during the second motion phase.
